DESIGN FOR A BRASSIÈRE OR THE LIKE

William Rosenthal, New York, N. Y., assignor to
Maiden Form Brassiere Company, Inc., New
York, N. Y., a corporation of New York

Application August 2, 1940, Serial No. 94,141

Term of patent 7 years

To all whom it may concern:

Be it known that I, William Rosenthal, a citizen of the United States, residing at 115 Central Park West, in the county of New York and State of New York, have invented a new, original, and ornamental Design for a Brassière or the like, of which the following is a specification, reference being had to the accompanying drawing, forming part thereof.

In the drawing it will be found that:

Fig. 1 is a front elevational view of a brassière in extended position showing my new design; and

Fig. 2 is a rear elevational view of the brassière shown in Fig. 1.

While my design is shown in the drawing as applied to a brassière, it is to be understood that the same is applicable to any lady's garment having a breast-supporting portion.

I claim:

The ornamental design for a brassière or the like, substantially as shown and described.

WILLIAM ROSENTHAL.
